MOLDING FOR A TABLE OR SIMILAR ARTICLE

Charles W. Clemens, Aurora, Ill.

Application October 22, 1957, Serial No. 48,200

Term of patent 14 years

(Cl. D54—2)

Figure 1 is a side perspective view of a molding for a table or similar article, showing my new design;

I claim:

The ornamental design for a molding for a table or similar article, substantially as shown.
